DECORATIVE GRILL FOR A SCREEN DOOR

Harry M. Riegelman, Rolling Hills, Calif., assignor to Ador Corporation, Fullerton, Calif., a corporation of California

Filed May 11, 1967, Ser. No. 7,079

Term of patent 14 years

(Cl. D54—2)

The grill is broken away at the center thereof in the several views to indicate indeterminate length.

I claim:

The ornamental design for a decorative grill for a screen door, as shown and described.
